WOMAN'S UNDERGARMENT

Enid Bissett, New York, N. Y., assignor to Maiden Form Brassiere Company, Inc., New York, N. Y., a corporation of New York

Application December 31, 1943, Serial No. 516,375

9 Claims.

(Cl. 2—224)

This invention relates to undergarments for women.

One object of the invention is a novel and improved undergarment for women which may be used as a slip or petticoat.

A further object of the invention is a novel and improved undergarment for women of the above indicated character which may be used as panties.

A further object of the invention is a novel and improved undergarment which functions both as a petticoat and panties and is characterized by the comfort to the wearer whether sitting, standing or walking.

A further object is such an undergarment which is characterized by the simplicity of its design and the economy with which it may be made.

More specifically my invention resides in an undergarment of the above indicated character whose upper part consists of a special yoke construction and design combined with a lower part correlated and cooperatively functioning therewith to produce a form-fitting and otherwise highly useful and desirable combined undergarment.

For a better understanding of the invention reference may be had to the accompanying drawings forming a part of this application, wherein

Fig. 1 is a perspective view of a garment embodying the invention;

Fig. 2 is a front view thereof; and

Fig. 3 is a back view thereof.

Referring to the drawing, I have illustrated my invention as embodied in an undergarment for women comprising an upper part 1 and a depending part 2. The depending part 2 is provided with a crotch 3 disposed at approximately halfway down the depending or flaring part 2, and thereby providing a pair of abbreviated shorts or leg parts 4 at the extreme bottom. The upper part consists of a special yoke the upper edge 5 of which fits on the waistline of the wearer. The yoke forms the upper half of the garment above the crotch 3, its lower edges in the front and back being indicated at 6 and 7 respectively. In the particular embodiment shown the depth of the yoke at the front and back is slightly more than half the distance from the upper edge 5 to the crotch 3. The lower border parts 6 and 7 of the yoke are of shorter length than the width of the waistline 5 and the yoke is cut on both sides to form inverted V's having sides 6', 7', these side border lines of the yoke forming acute angles with the front and back bottom border lines 6 and 7 and in the particular embodiment shown roughly 45°. The yoke on either side has a length 8', measured between the vertex of the V and the upper edge 5 which is approximately half the

depth of the yoke at the front and back. The part 2 depending from the yoke including the leg parts 4 is cut very full so as to give the petticoat effect, and the particular form of yoke, with depths at the front and back approximating half or more the depth of the garment to the crotch 3 and the deep inverted V cuts on the sides, permit the desired fullness to be given to the garment. The particular design of yoke and depending part including the side V cuts also avoids the necessity for gathering or shirring.

The yoke 1 in addition to forming approximately the upper half of the garment above the crotch 3 and having the inverted V shapes on the side, is also cut on the bias so as to yield vertically and horizontally while the depending part 2 is not cut on the bias. The bias cut of the yoke and the non-bias cut of the depending part 2 of the garment together with the particular cut and form of the yoke being cut deep in the front and back and being provided with the V cuts on the side, render the garment form-fitting and at the same time provides the flare desired for freedom of movement. The underskirt or petticoat effect is obtained along with the protection afforded by panties. This single garment therefore can be used in the place of the conventional petticoat and panties. Due to the particular structural design of the yoke and the fact that it gives or yields both crosswise and up and down it yieldingly adjusts itself to form fit the waist and hips of the wearer and at the same time there is, due to the correlated design of the depending part 2, complete freedom of body movement along with perfect comfort for both sitting and standing. The bottom or leg parts 4 of the garment are made very full to facilitate the freedom of movement. There is no gathering anywhere in the garment. The cuts are all along straight lines 5, 6, 6', 7, 7', 8, 8', 9, 10 and 12 thereby facilitating the making of the garment with marked economy in expense and the form fitting being provided notwithstanding the simple design. The proportions of the garment are such that the garment crotch 3 is substantially below the crotch of the wearer but by reason of the particular cut and design there is no discomfort to the wearer. The seam lines 12 diverge upwardly from the upper ends of the seams 9 and terminate at the middle points of the front and back border lines 6 and 7 respectively. There is no pull in the wearing of the garment and in short it accommodates itself to all the movements of the body, sitting, standing, bending, walking and running.

The particular design of deeply cut yoke gives a girdle effect with no wrinkles and no fullness and eliminates the necessity of gathers in the depending part and moreover allows a wider

and fuller dependent and leg part, giving adequate room for sitting down with no gathering, as indicated, in the dependent part but with the fullness desired. Moreover, the deep cut of the yoke which, as pointed out above, is cut on the bias, results in a proportionate increase in the give or yield and freedom of movement whereas a substantially smaller depth would result in a disproportionate less freedom of movement. Moreover, a smaller relative depth of yoke would result in the tendency to ride up whereas in the particular design shown and described above it stays in place and allows great freedom of the depending part. The deep inverted V cuts on the side of the yoke contribute to the functioning of the yoke and depending part described, that is the yoke stays in place with adequate room in the depending part without gathering.

In the particular embodiment shown a conventional zipper fastener 11 is provided on one side for opening up the waist to facilitate removal and putting on of the garment.

The garment may be of any suitable underwear materials as for example, silks, nylons, rayons, silk jersey, cottons, linens and the like and I have obtained particularly goods results with the use of the same material for the yoke part 1 and the depending part 2 with the yoke part 1 cut on the bias and the depending part 2 not cut on the bias.

I claim:

1. An undergarment for women comprising an upper yoke part cut deep in the back and front having inverted V cuts on the sides and a depending skirt part divided at the bottom into separate portions for the legs, the yoke part being cut on the bias and the depending part being cut full to give a petticoat effect, the upper edge of said yoke being adapted to be fastened about the waistline of the wearer and the yoke being of sufficient depth in the rear substantially to cover the hips.

2. An undergarment for women comprising an upper yoke part of substantial depth extending all the way around the hips and of sufficient depth in the rear substantially to cover the hips, said yoke having inverted V cuts on the sides with the vertices of the V's extending upwardly approximately half the depth of the yoke, and a skirt part depending from the yoke and divided at the bottom into separate portions for the legs and being cut full to give a petticoat effect, the upper edge of the yoke being adapted to be fastened about the waistline of the wearer and the garment crotch being disposed below the lower edges of the front and back of the yoke a distance approximately the depth of the yoke.

3. A women's petticoat comprising at the top a yoke which is cut on the bias and a skirt part depending from the yoke which is divided at the bottom to form separate portions for the legs, said yoke having sufficient depth in the rear substantially to cover the hips and the crotch of the leg portions being approximately halfway the length of the depending skirt.

4. A women's petticoat comprising at the top a yoke which is cut on the bias and a skirt part depending from the yoke which is divided at the bottom to form separate portions for the legs, said yoke having a depth in the rear and front sufficient to cover the hips and having deep inverted V cuts on the sides, with the crotch of the leg portions disposed substantially midway the length

of the skirt part below the yoke and the skirt part being cut full to give a petticoat effect.

5. An undergarment for women comprising a form-fitting upper yoke part of substantial depth extending all the way around the hips and waist and of sufficient depth in the front and rear substantially to cover the hips, said yoke having inverted V cuts on the sides with the vertices of the V's extending upwardly a substantial part of the depth of the yoke, and a skirt part depending from the yoke and divided at the bottom into separate portions for the legs and being cut full to give a petticoat effect, the upper edge of the yoke being adapted to be fastened about the waistline of the wearer and the garment crotch being disposed below the lower edges of the front and back of the yoke a substantial distance.

6. A women's petticoat comprising at the top a yoke which is cut on the bias and a skirt part depending from the yoke which is divided at the bottom to form separate portions for the legs, the seams of the petticoat being formed along straight lines.

7. A women's petticoat comprising an upper yoke part of substantial depth all the way around and of sufficient depth in the rear substantially to cover the hips, and a skirt part depending from the yoke divided at the bottom into separate portions for the legs and cut full to give a petticoat effect, the upper edge of the yoke being adapted to be fastened about the waistline of the wearer and the garment crotch being disposed below the lower edge of the yoke at the rear and spaced therefrom and from the crotch line of the wearer a distance approximately the depth of the yoke at the back, the cuts of the parts being along straight lines and the garment being form-fitting with the skirt part depending downwardly to give the petticoat effect without gathering or Shirring.

8. A women's petticoat comprising at the top yoke parts which are cut deep in the back and front with the back part extending to the lower part of the hips, said yoke parts having diverging side lines and a skirt part depending from the yoke parts and divided at the bottom into separate portions for the legs, said portions being cut full, but without gathering or Shirring, to give a petticoat effect, the upper edges of the yoke parts being adapted to be fastened about the waistline of the wearer and the garment being form-fitting about the hips with the crotch of the depending skirt part disposed below the lowest part of the yoke and spaced therefrom a substantial distance.

9. A women's petticoat comprising at the top yoke parts which are cut deep in the back and front with the back part extending to the lower part of the hips, said yoke parts having diverging side lines and a skirt part depending from the yoke parts and divided at the bottom into separate portions for the legs, said portions being cut full, but without gathering or Shirring, to give a petticoat effect, the upper edges of the yoke parts being adapted to be fastened about the waistline of the wearer and the garment being form-fitting about the hips with the crotch of the depending skirt part disposed below the lowest part of the yoke and spaced therefrom a substantial distance, the cuts and seams of the garment being along straight lines.

ENID BISSETT.
